UNITED STATES PATENT OFFICE.

ALBERT L. LENGEL, OF BAKERSFIELD, CALIFORNIA.

AUTOMATIC INKING DEVICE FOR PRINTING PRESSES.

Application filed December 29, 1922. Serial No. 609,694.

To all whom it may concern:

Be it known that I, ALBERT L. LENGEL, a citizen of the United States, residing at Bakersfield, in the county of Kern and State of California, have invented new and useful Improvements in Automatic Inking Devices for Printing Presses, of which the following is a specification.

This invention relates to printing presses and more particularly to automatic inking apparatus for printing presses.

The present systems of ink supply are controlled at all times during a press run by adjustable impression screws of one description or another, all having the same effect of pressing on a steel blade, which in turn controls the flow of ink presented to the doctor rollers which in turn transfers ink to inking surfaces. This flow of ink is necessarily readjusted every time the form is changed due to the difference in makeup of the forms, and to the unequal demand for ink on any form. Also this adjustment must continue to be manipulated with varying speeds.

My object is to provide means that will set "color" automatically, in that a perfect film of ink will be presented to the characters to be printed, such depth of film to be the "color" desired for successive or diversified consecutive forms or plates, as beforehand determined and so set, and not being again necessary of readjustment until such wear of roller surfaces or possible shrinkage or warping of vital parts makes a realignment of the fountain blade necessary, to produce the depth of "color" desired for consecutive diversified printing forms or plates.

Other objects and advantages will be made manifest in the following specification of an embodiment of the invention illustrated in the accompanying drawings, wherein—

Figure 1 is a diagrammatic view showing the improved inking mechanism.

Fig. 2 is a cross section of an improved form of fountain roller.

Ink fountains I are variable in width as are the presses. However, reinforcing posts are used to afford rigidity to the fountain cover, which in turn supports the ink flow control blade B, which is tightly bolted between fountain cover and adjustment screw board, leaving such amount of blade exposed to insure a spring tension effect, gov-

erned by adjustment screws, pressing the blade into contact desired, with a fountain roller. (Reinforcing posts may be placed about twelve inches apart and adjustment screws about two inches apart, the width of any fountain.)

1 is the fountain roller composed of rubber, vegetable composition, or any kindred substance affording a flexible surface 1^a, this roller to be cast with a canvas, or like cloth substance covering, which presents an irregular surface, in that it has small pits on its surface. These small pits serve to convey the desired film of ink to the printing characters, as ordained by the set of the fountain blade B, pressing deeply into them or passing over the top of them; the flexible surface of the roller permitting a perfect contact of ink and printing surface.

2 is the plate or form cylinder upon which is placed a sufficient amount of ink to produce the desired "color." But the ink, being applied in small mounds, is preferably smoothed out to even the film, which is done in the following manner:

The rough film of ink received by the plate or form 2 immediately comes in contact with a heavy duty transfer roller 3 which irons out and picks up an oversupply of ink on the edges of characters and deposits such oversupply on a sun roller 4. Such oversupply of ink next comes in contact with vibrating rollers 7, which further smooths out the film of ink. Thus smoothed, the oversupply comes in contact with the finishing form rollers 5, which further evens the film of ink on the printing plates or forms, before coming in contact with the paper or substance to be printed on, which passes between cylinders 2 and 6.

Preferably all inking surfaces are of different diameters, namely cylinders 1—2—3—4—7, to prevent the same identical surfaces coming in contact consecutively, thus insuring a more uniform "color." Also all rollers used except the fountain roller, are of the latest type and formula, at present accepted and used in the printing industry.

The diagram indicates two impressions on a printed product, showing versatility of arrangement, easily adapted to any desired press arrangement, either commercial or newspaper, the diagram, however, is one of a possible arrangement of a unit of a newspaper press.

Where it is necessary to set "color" after a press run is on the press, as is now the case, the advantages of being able to produce a perfectly colored product with the 5 first impressions, thus saving considerable time in slow running until the "color" can be set, can readily be seen. This improvement results in also improving the appearance of the product and saving of much 10 waste and poorly printed products, and producing perfectly colored printing all through a run of any length, whereas now the coloring must be continually touched up even after the press has been running 15 for some time, due to the natural tendency of present methods to gather dirt or surfaces, to intermittent induction of ink, and to the lower ink level in the fountains as the run progresses. Also, I accomplish a 20 saving in man power, heretofore required to keep "color" set, and insure a perfect color effect on all pages of a product, impossible to secure by hand setting.

Thus I have produced an inking system 25 comprising an ink fountain, a soft cloth-covered roller in the fountain, a printing cylinder in contact with the fountain roller, a transfer roller in contact with the cylinder, said cylinder rotating from the fountain 30 roller towards the transfer roller, a sun roller in contact with the transfer roller, a plurality of distributing rollers in contact with the sun roller, and a finishing roller in contact with the sun roller and 35 with the cylinder at the opposite side of the distributing roller from the fountain roller, so that plenty of ink is applied to the printing cylinder by the fountain roller, the surplus gobs of ink taken from the 40 printing cylinder by the transfer roller and worked upon the sun roller and carried back to the printing cylinder by the finishing roller, all before the printing face reaches the impression roller.

45 Further embodiments, modifications and changes may be resorted to within the spirit of the invention as here claimed.

What is claimed is:

1. Inking apparatus for printing presses 50 comprising, in combination, a printing form, a fountain having a cloth faced fountain roller engaging said form, an impression member between which and the said form the sheet to be printed is run, and a system of ink distributing rollers certain of 55 which engage the form at a portion thereof after the deposit of ink thereon by the said fountain roller and prior to the engagement by the printing form of said impression member.

2. Inking apparatus for printing presses 60 comprising, in combination, a printing form, a fountain having a fountain roller engaging said form, an impression member 65 between which and the said form the sheet

to be printed is run, and a system of ink distributing rollers certain of which engage the form at a portion thereof after the deposit of ink thereon by the said fountain roller and prior to the engagement by the 70 printing form of said impression member, said system including a sun roller and a plurality of rollers all engaging the sun roller and certain of which rollers engage the form. 75

3. Inking apparatus for printing presses comprising, in combination, a printing form, an ink fountain having means for applying ink to said form, an impression member between which and the printing form the sheet to be printed is run, a sun roller, and a system of rollers each having contact with the sun roller and certain of which have contact with the form whereby ink applied to the form from the fountain 80 is transferred to the sun roller and is smoothed out by the rollers engaging said sun roller and the finished ink returned to the form. 85

4. In inking apparatus for printing presses comprising, in combination, a printing form, an ink fountain having means for applying ink to said form, an impression member between which and the printing form the sheet to be printed is run, a sun roller, and a system of rollers each having contact with the sun roller and certain of which have contact with the form whereby ink applied to the form from the fountain is transferred to the sun roller 90 and is smoothed out by the rollers engaging said sun roller and returned to the form, the system of rollers being interposed to engage a zone of the form between the ink applying means and the impression member. 95

5. Inking apparatus for printing presses comprising, in combination, a printing form, an ink fountain having means for supplying ink to said form, an impression member between which and the printing form the sheet to be printed is run, a sun roller, and a system of rollers each having contact with the sun roller and certain of which have contact with the form whereby ink applied to the form from the fountain 100 is transferred to the sun roller and is smoothed out by the rollers engaging said sun roller, and returned to the form, the rollers of said system being each of different diameter from the others. 105

6. An inking system comprising an ink fountain, a soft cloth-covered roller in the fountain, a printing cylinder in contact with the fountain roller, a transfer roller 115 in contact with the cylinder, said cylinder rotating from the fountain roller towards the transfer roller, a sun roller in contact with the transfer roller, a plurality of distributing rollers in contact with the sun 120 roller. 125

roller, and a finishing roller in contact with the sun roller and with the cylinder at the opposite side of the distributing roller from the fountain roller, so that plenty of ink is applied to the printing cylinder by the fountain roller, the surplus gobs of ink taken from the printing cylinder by the transfer roller and worked upon the sun roller and carried back to the printing cylinder by the finishing roller, all before the 10 printing face reaches the impression roller. In testimony whereof I have signed my name to this specification.

ALBERT L. LENGEL.
